ASH AND SOOT TRAP

Harold F. Burnaugh, Denver, Colo.

Application April 3, 1936, Serial No. 72,639

1 Claim. (Cl. 126—280)

This invention appertains to new and useful improvements in traps for catching ash and soot in furnace flues.

The principal object of the present invention is to provide means for collecting ash and soot which normally is drawn into the flue pipe and flue and frequently collects and forms deposits in the flue pipe and flue resulting in hindrance of the draft and frequently resulting in flue fires.

Another important object of the invention is to provide a trap for catching ash and soot substances before they enter the furnace flue pipe and flue wherein means is provided whereby the trap can be emptied conveniently and without disagreeableness to the person manipulating the same.

Other important objects and advantages of the invention will become apparent to the reader of the following specification.

In the drawing:

Figure 1 is a vertical sectional view through the trap;

Figure 2 is a side elevational view of the flue attaching pipe section.

The trap consists of a cylindrical shell 9 provided with a downwardly tapering hopper-like lower portion 9a terminating in a reduced cylindrical neck 10 having slits in diametrically opposite portions thereof through which the slide valve 11 is slidable. The reduced cylindrical neck 10 is adjustable on the bottom of the trap so that it may be turned in any position to afford easy access to the slide valve. One end of this slide plate 11 is rolled over to provide a hand-grip 12, while the opposite end is provided with a down turned flange 13 to serve as a stop.

The bottom of the neck 10 is provided with an elongated rectangular-shaped opening 14 merging at its intermediate portion with a circular opening 15 and one end portion of the slide plate 11 is provided with an opening 16 of substantially the same shape as the opening 15, so that when the plate 11 is slid to the right in Figure 1, the opening 16 will register with the opening 15, so that the contents of the shell can fall out into a suitable collecting receptacle.

Small brackets 17 are provided in the neck portion 10 of the shell for supporting the vertically extending tube 18. This tube 18 serves as a draft-promoting factor so that when the ashes and soot are being emptied from the shell 9 any

fine substances will be sucked up the flue pipe section 20 instead of permeating the atmosphere outside of the shell 9 and perhaps soiling the clothes of the person performing this operation.

A small lug 21 is secured to the upper portion of the shell 9 and has an opening 22 therein through which the lower end of a cable or wire can be disposed. This wire 23 can be anchored at its upper end to a joist or ceiling so as to assist in supporting the trap.

Numerical 23 is a nipple projecting laterally from the shell 9 for attachment with the flue connection of the furnace, while the flue pipe section 20 is connected by an elbow to a flue leading to the usual chimney. To permit the escape of all gases and smoke from shell 9 to readily rise up the flue with a coasting or draft checked fire, an opening 25 is provided in the pipe section 20 adjacent the top of the shell 9 at the opposite side portion of the pipe section 20 from the inlet 20 nipple 26.

The lower end of the pipe section 20 is below the level of the nipple 26 so that incoming gases and substances from the furnace will be caused to take a downward route or an indirect route up 25 the flue pipe section 20, and in this tortuous route any precipitation of the substances will be collected in the lower portion of the shell. Thus, a high percentage of all substances in the flue gases will be collected in the shell 9 instead of 30 going up the flue and perhaps collecting therein.

While the foregoing specification sets forth the invention in specific terms, it is to be understood that numerous changes in the shape, size, and materials may be resorted to without departing 35 from the spirit and scope of the invention as claimed hereinafter.

Having described the invention, what is claimed is:

A soot and ash trap for flues comprising a shell 40 having an inlet in the side thereof, an outlet pipe section extending downwardly from the top of the shell and terminating at its lower end below the said inlet, a valve in the lower portion of the shell which can be opened to permit emptying of 45 the shell, and a vertically extending tube supported in the shell, said tube being open at both ends and having its lower end terminating adjacent the said valve.

HAROLD F. BURNAUGH.
